UNITED STATES PATENT OFFICE.

JOSEPH C. HAMES, OF GOLDFIELD, NEVADA.

KNOCKDOWN TANK.

No. 872,813.

Specification of Letters Patent.

Patented Dec. 3, 1907.

Application filed April 8, 1907. Serial No. 367,021.

To all whom it may concern:

Be it known that I, JOSEPH C. HAMES, a citizen of the United States, residing at Goldfield, in the county of Esmeralda and State of Nevada, have invented new and useful Improvements in Knockdown Tanks, of which the following is a specification.

My invention pertains to tanks and more particularly to tanks for use in the treatment of ores; and it has for its object to provide a simple, inexpensive and durable knockdown tank—*i. e.*, a tank adapted to be transported in a knocked down condition and to be expeditiously and easily set up ready for use.

With the foregoing in mind, the invention will be fully understood from the following description and claims when the same are read in connection with the accompanying drawings, forming part of this specification, in which:

Figure 1 is a broken side elevation of a portion of a knockdown tank constructed in accordance with my invention. Fig. 2 is a broken end elevation of a portion of the tank.

Similar letters of reference designate corresponding parts in both views of the drawings.

My novel knockdown tank is constructed in the manner illustrated—that is to say, it comprises transverse stringers A of wood, arranged a suitable distance apart, a bottom wall B, of stone, wood or other preferred material, side walls C of wood, arranged against opposite longitudinal edges of the bottom wall B, Fig. 1, end walls D of wood, arranged against the opposite ends of the bottom wall and connected to the side walls C through the medium of strap bolts E fixedly fastened on the side walls C, Fig. 1, and disposed in notches F in the end walls, Figs. 1 and 2, side posts G of wood, arranged at the outer sides of the side walls and parallel to the extended end portions of the stringers A, metallic straps K disposed at the opposite sides of the extended portions of the stringers A, with reference to the posts G, and connected to said stringers A and posts G through the medium of longitudinally-disposed bolts L, longitudinally-disposed bolts M extending transversely through the stringers A in vertical planes between the vertical planes of the side walls

C, longitudinally-disposed bolts N connected to the upper ends of the straps K and disposed at the outer sides of the posts G, transversely disposed bolts P extending through and connecting eyes on the bolts M and N and disposed at the opposite sides of the posts G, with reference to the stringers A, and having for their office to draw the side posts G and the side walls C tight against the longitudinal edges of the bottom wall B and securely lock said posts G and side walls C in such positions, bolts Q extending through and connecting the side walls C and the side posts G, channeled lugs R bolted to sides of the posts G, and bolts S fixed to the side walls C, extending downward through the channels in the lugs R and provided below the said lugs R with nuts, as shown, whereby the side walls may be drawn down against and securely held on the stringers A. When the side walls C are thus drawn down on the stringers A, the bolts Q connecting the posts G and the side walls C play in slots T provided in the said posts G, and hence do not interfere in any measure with the tightening of the side walls C against the stringers A.

In virtue of the construction set forth, it will be observed that the tank may be shipped or transported in a knocked-down state, and when it reaches its destination may be expeditiously and easily set up without the employment of skilled labor; also, that the construction is sturdy and durable and therefore well adapted to withstand the rough usage to which tanks used in the treatment of ore are ordinarily subjected.

When desired, one of the end walls of the tank may be provided with one or more doors U, Fig. 2, preferably of metal, for use when it is desired to flush and clean the tank.

I have entered into a detailed description of the construction and relative arrangement of the parts embraced in the present and preferred embodiment of my invention in order to impart a full, clear and exact understanding of the said embodiment. I do not desire, however, to be understood as confining myself to such specific construction and relative arrangement of parts as such changes or modifications may be made in practice as fairly fall within the scope of my invention as claimed.

Having described my invention, what I claim and desire to secure by Letters-Patent, is:

1. A knockdown tank comprising a bottom wall, side walls abutting against opposite edges of the bottom wall, end walls also abutting against opposite edges of the bottom wall and having notches in their ends, cross-wise stringers disposed below the bottom wall and extending beyond the vertical planes of the side walls, upright posts disposed alongside of the extended portions of the stringers and at the outer sides of the side walls, strap bolts connected to the side walls and disposed in the notches of the end walls, metallic straps K connected to the opposite sides of the extended portions of the stringers, with reference to the upright posts, and extending above the extended portions of the stringers, longitudinally-disposed eye-bolts N connected to the said straps and extending across the outer sides of the upright posts, longitudinally-disposed eye-bolts M extending through the stringers and disposed in vertical planes between those of the side walls, and transversely-disposed bolts P connecting the said eye-bolts M and N and arranged to draw the side walls in against the edges of the bottom wall.
2. In a knockdown tank, the combination of a bottom wall, side walls abutting against opposite edges of the bottom wall, end walls connected with the side walls, cross-wise stringers disposed below the bottom wall and extending beyond the vertical planes of the side walls, upright posts disposed alongside

of the extended portions of the stringers and at the outer sides of the side walls and connected with said side wall, metallic straps K connected to the opposite sides of the extended portions of the stringers, with reference to the upright posts, and extending above the extended portions of the stringers, longitudinally-disposed eye-bolts N connected to the said straps and extending across the outer sides of the upright posts, longitudinally-disposed eye-bolts M extending through the stringers and disposed in vertical planes between those of the side walls, and transversely-disposed bolts P connecting the said eye-bolts M and N and arranged to draw the side walls in against the edges of the bottom wall.

3. A knockdown tank comprising a bottom wall, side walls abutting against opposite edges of the bottom wall, end walls also abutting against opposite edges of the bottom wall and connected with the side walls, stringers disposed below the bottom wall and extending beyond the vertical planes of the side walls, upright posts disposed alongside of and connected with the extended portions of the stringers and having vertical slots, bolts extending through said slots and connecting the posts and the side walls, lugs connected to sides of the upright posts, bolts connected to the side walls, above the lugs, and extending downwardly through the lugs, and nuts mounted on said bolts and disposed below the lugs.

In testimony whereof I have hereunto set my hand in presence of two subscribing witnesses.

JOSEPH C. HAMES.
